Franklin Harris

ATTORNEYS.

UNITED STATES PATENT OFFICE.

CHARLES E. H. LLOYD, OF LOS ANGELES, CALIFORNIA.

HYDRAULIC PUMP AND SYSTEM.

Application filed June 30, 1924. Serial No. 723,199.

To all whom it may concern:

Be it known that I, CHARLES E. H. LLOYD, a citizen of the United States, residing at Los Angeles, in the county of Los Angeles, State of California, have invented a new and useful Hydraulic Pump and System, of which the following is a specification.

My present invention comprises not only a novel hydraulic pump, but a system comprising the same; and it is an especial object of this invention to provide effective hydraulic means, dispensing with a sucker rod, for imparting movement to a plunger at the bottom of a deep well, such as, for example, a California oil well.

It is an object of this invention to provide a pump suitable to be secured at the lower end of a string of tubing through which oil may be delivered, the said tubing being carried to any desired depth of submergence, and the plunger of the submerged pump being reciprocated by means of an operating fluid delivered alternately above and below a piston rigidly connected with said plunger and operating in a cylinder or a working barrel of suitable diameter, the operating fluid being preferably alternately driven in opposite directions through a pair of pipes extending to the surface of the ground; and, in a preferred embodiment of my invention, one of said pipes may be carried through the mentioned reciprocating piston, and the latter may also be provided with unique packing hereinafter described.

Although the operating fluid employed in my pump may be of any preferred character, when the same is employed in an oil well, I consider it advantageous to simplify all problems of leakage and lubrication, by using, as an operating fluid, an oil, such as a partially or completely refined lower-boiling fraction obtained from the oil pumped; and although the desired pulsations or alternating movements of the operating liquid may be obtained in any desired manner, my invention may comprise also novel means hereinafter described for forcing the operating liquid downward, first in one and then in the other of two operating fluid pipes carried into the upper end of the submerged pump.

My invention comprises also certain features of valve control and pressure control in specific combination as hereinafter set forth,

Other objects of my invention will appear from the following description of alternative embodiments thereof, taken in connection with the appended claims and the accompanying drawings, in which

Fig. 1 is a substantially central but somewhat diagrammatic section through the working barrel, plunger and associated submerged parts of a pump embodying my invention, all details of packing and gland construction being omitted or shown conventionally.

Fig. 2 illustrates a horizontal section substantially on the line 2—2 of Fig. 1.

Fig. 3 shows an advantageous type of packing hereinafter referred to.

Fig. 4 is a diagrammatic view of an organization comprising a pump of the character shown in Fig. 1, in association with one advantageous type of head for operating the same, by a liquid under pressure.

Fig. 5 is a diagrammatic view inserted merely to illustrate certain principles of operation hereinafter discussed as especially suitable for use in my novel pump.

Referring first to the details of construction illustrated in Figs. 1, 2 and 3, 11 may be a plunger in the form of a substantially cylindrical body provided at its lower end with a valve 12, this plunger being longitudinally movable relatively to a pump barrel comprising a cylinder 13, within which said plunger is movable by means of a piston 14, preferably integral therewith or rigidly secured thereto. The upper and lower ends of the cylinder 13 may have threaded engagement with heads 15 and 16, through which the plunger at 11 reciprocates; and a sub 17, or its equivalent, secured to the lower head 16 may be provided with a standing valve 18, adapted to prevent any return or downward movement of oil or other liquid therethrough. By the construction referred to, suitable packing may be provided at 19 and 20, to prevent leakage between the plunger 11 and the fixed heads 15, 16, any reciprocation of the plunger 11 being effective to lift oil through the entire string 21, with which the upper head 15 may be connected by an upper sub 22.

To provide for the hydraulic reciprocation of the piston 14, or its equivalent, I may introduce an operating fluid first through one and then through the other of the substantially parallel pipes 23, 24, both of these

pipes being carried through the upper head 15 and a part or extension of one of said pipes, for example, a polished section 24' of the pipe 24, shown as connected by a union 25, being carried through the piston 14 and terminated at a low level therebelow in such manner as to permit the introduction or withdrawal of an operating fluid from a lower piston chamber 26, cooperating in function with an upper piston chamber 27, into which extends the pipe 23. Although any preferred type of packing may be retained at 19 and 20 by the gland bushings 28, 29, I consider it advantageous to employ metallic packing of the general character shown in Fig. 3, a convex packing ring 30 and a superimposed concave ring 31 of corresponding taper being preferably associated with rings rectangular in cross-sectional outline, such as the outer ring 32 provided at the inner edge thereof with a groove or channel to receive an inner ring 33. The diagonally cut ends of the respective rings are preferably staggered, in a known manner, the entire assembly of unlike rings being duplicated or repeated as extensively as may be found necessary to assure continuous and reliable operation, without occasioning withdrawal for replacement or repair.

30 Although an organization embodying the features above referred to may be comparatively complex, as in the case of a plant equipped not only for the recovery of a raw oil, but for the refining thereof (in which case the raw oil may be carried, for example, through storage tanks to a still, from which a suitable condensate or residue may be taken for use as an operating fluid maintained under pressure and driven alternately in opposite directions through the pipes 23, 24, or their equivalents), essential principles of operation of my invention may perhaps be best understood by the consideration of a purely schematic representation 45 of a comparatively simple embodiment thereof, as illustrated in Fig. 5. In this figure, the pipes 23' and 24' are shown as respectively connected with opposite ends of a cylinder 34, within which is reciprocated an actuating piston 35, the movements of the pump plunger 11' being dependent upon the reciprocation of this piston 35', as by means of a rod 36. The latter may be driven backward and forward in any desired way, the use of a rotating cam 37 being suggested primarily because of its pictorial simplicity and because a cam groove 38 may be varied in design to control the timing of the respective up and down 50 strokes in any desired manner. All parts of the operating system may be kept constantly filled with the selected oil, or with any preferred operating fluid, and leakage and expansion may be compensated for by 55 any suitable means, as by providing in-

wardly opening valves 39, 40, preferably at or near the opposite ends of the cylinder 34. Pressure within this system may be limited in any suitable way, as by the employment of a pressure valve 41 in any suitable pipe 70 or pipes of the system, an outlet past this valve being shown as connected with a return pipe 42, which may lead toward a pressure fluid supply tank 43, kept under any suitable pressure and connected with the 75 mentioned inwardly opening valves 39, 40, as by pipes 44, 45.

Instead of producing pressure by means of the piston 35, or its equivalent, I may, as illustrated in Fig. 4, employ means such 80 as a piston 35' primarily for the purpose of timing the alternations of pressure on opposite sides of the piston 14 associated with the plunger 11,—driving power being in this case supplied by the maintenance of a suitable pressure in a primary reservoir or supply tank 43', into which the operating fluid may be forced by means such as a pump P. In this embodiment of my invention, valves 46, 47, leading respectively to the channels 85 48, 49 with which the pipes 23 and 24 are respectively connected, may be alternately closed by means such as an additional valve piston 50, shown as secured to a rod 61, separated from but aligned with the respective 90 valve stems 51, 52 of the valves 46, 47. The operating fluid being admitted past a pressure valve 53 through the inlet ports 54, 55, the pressure of said operating fluid may obviously be applied to either side of the 100 piston 14, according as one or the other of the valves 46, 47 is opened, it being obvious that when the operating fluid is forced downwardly in one of the pipes 23, 24, it must be permitted to rise through the other 105 of said pipes, as by allowing it to return to one or the other of the chambers 48, 49.

To control the reciprocation of the piston 50, I may employ means such as a three-way valve 56, an entrance port to this valve being connected with a branch 57 from the pipe 58, through which the pressure fluid is supplied, and passages 59, 60 being provided between said valve and the respective chambers 62 on opposite sides of the valve piston 50, the passages 59 and 60 being adapted to serve alternately as inlet and outlet passages, according to the position of the valve 110 56, and the "exhaust" from one or the other of the chambers 62, being permitted to exit in any suitable way, as through an inner sleeve 63 of the valve 56. The latter is shown as provided with an operating arm 64, to which movements in opposite directions may be imparted by means such as tappets 65, 66 115 on a sliding rod 67, the latter being in turn movable by successive and alternating engagements of the arms 68, 69, adjustably mounted on opposite ends of the piston rod 70, rigidly connected with the piston 35, 120 125 130

these arms 68, 69 being adapted to contact with the adjustable tappets 70, 71 on the sliding rod 67.

It will be obvious that when the piston 14, 5 or its equivalent, is moved alternately in opposite directions by means of pressure transmitted directly or indirectly from a reservoir 43' or its equivalent, the operativeness of my device is conditioned upon the provision 10 of some suitable means permitting the return or escape of used portions of operating fluid after power has been derived from the motion thereof. For this last mentioned purpose, any suitably timed or operated 15 valves may be provided, as, for example, the valves 73, 74, movable by arms engaged by adjustable means, such as the mentioned tappets 70, 71 and additional tappets 75, 76. Pressure valves may be provided, and it will 20 be understood that all "exhaust" fluid, including that which may escape the outlet 63 of the valve 56, may be collected in a sump (not shown) or elsewhere and returned by pump P to tank 43' or otherwise conserved. 25 In the organization last described, it will be understood that, instead of employing means such as a pitman connected at 79 to impart positive movement to the rod 70, or its equivalent, thereby using the movement 30 of the piston 35 to drive the operating fluid and reciprocate plunger 11, I may employ said piston merely as a part of a valve control system, the timing of all cooperating elements in the operating organization 35 shown in Fig. 4 being variable by the adjustment of the arms 68, 69 or their equivalent, and by the adjustment of means such as the respective tappets optionally mounted, as described, on the sliding rod 67. It will 40 be understood that, in any operating organization of the general type disclosed in Figs. 4 and 5, the capacity of the cylinder or surge tank C' is intended to be substantially greater than that of the lower cylinder 13, 45 in order to permit of any necessary allowance for leakage or expansion and contraction; and also that the described adjustments, or the form of the cam groove of cam 37, should be such as to keep the plunger 50 11 or piston 14 from reaching an extreme or "bumping" position and such as to permit the lifting stroke to occupy any desired fraction of the time required for a complete cycle of operations. 55 Although, I have herein described and diagrammatically illustrated a comparatively complete typical embodiment of my invention, it will be understood that the various features thereof might be independently employed and also that numerous additional 60 modifications might be devised by those skilled in the art, without the slightest departure from the spirit and scope of my invention, as the same is indicated above and in the following claims.

I claim as my invention:

1. In a pumping system, the combination of: an hydraulic pump comprising a plunger carrying a piston; a pressure supply tank adapted to contain an operating liquid; 70 pipes extending from said tank and to said pump; and an interposed operating head comprising means for varying the alternations of pressure through said pipes on opposite sides of said plunger, said means comprising a cylinder, a second piston adapted to reciprocate in said cylinder, a rod extending from each side of said second piston, and valves on the free ends of said rod, said valves being adapted to open and close 80 passages in said pipes.

2. In a pumping system, the combination of: an hydraulic pump comprising a plunger carrying a piston; a pressure supply tank adapted to contain an operating liquid; 85 pipes extending from said tank and to said pump; and an interposed operating head comprising means for varying the alternations of pressure through said pipes on opposite sides of said plunger, said means comprising a branch pipe line from one of said pipes, a cylinder connected to said branch line, a second piston adapted to reciprocate in said cylinder, a rod extending from each side of said second piston, and valves on the 90 free ends of said rod, said valves being adapted to open and close passages in said pipes.

3. In a pumping system, the combination of: an hydraulic pump comprising a plunger carrying a piston; a pressure supply tank adapted to contain an operating liquid; 100 pipes extending from said tank and to said pump; and an interposed operating head comprising means for varying the alternations of pressure through said pipes on opposite sides of said plunger, said means comprising a cylinder, a second piston adapted to reciprocate in said cylinder, a rod extending from each side of said second piston, 105 valves on the free ends of said rod, said valve being adapted to open and close passages in said pipes, and a valve for controlling the movement of said second piston.

4. In a pumping system, the combination of: an hydraulic pump comprising: a plunger carrying a piston; a pressure supply tank adapted to contain an operating liquid; 110 pipes extending from said tank and to said pump; and an interposed operating head comprising means for varying the alternations of pressure through said pipes on opposite sides of said plunger, said means comprising a cylinder, a second piston adapted to reciprocate in said cylinder, a rod extending from each side of said second piston, 115 valves on the free ends of said rod, said valves being adapted to open and close passages in said pipes, a valve for controlling the movement of said second piston, and 120

125

130

means for controlling the last mentioned valve.

5. In a pumping system, the combination of: an hydraulic pump comprising a plunger carrying a piston; a pressure supply tank adapted to contain an operating liquid; pipes extending from said tank and to said pump; and an interposed operating head comprising means for varying the alternations of pressure through said pipes on opposite sides of said plunger, said means comprising a cylinder, a second piston adapted to reciprocate in said cylinder, a rod extending from each side of said second piston, valves on the free ends of said rod, said valves being adapted to open and close passages in said pipes, a valve for controlling the movement of said second piston, and adjustable means for controlling the last mentioned valve.

6. In a pumping system, the combination of: an hydraulic pump comprising a plunger carrying a piston; a pressure supply tank adapted to contain an operating liquid; pipes extending from said tank and to said pump; and an interposed operating head comprising means for varying the alternations of pressure through said pipes on opposite sides of said plunger, said means comprising a cylinder, a second piston adapted to reciprocate in said cylinder, a rod extending from each side of said second piston, valves on the free ends of said rod, said valves being adapted to open and close passages in said pipes, a valve for controlling the movement of said second piston, a rod adapted to actuate the last mentioned valve, and a third piston operating in a cylinder for actuating the last mentioned rod.

40 7. In a pumping system, the combination of: an hydraulic pump comprising a plunger carrying a piston; a pressure supply tank adapted to contain an operating liquid;

pipes extending from said tank and to said pump; and an interposed operating head comprising means for varying the alternations of pressure through said pipes on opposite sides of said plunger, said means comprising a cylinder, a second piston adapted to reciprocate in said cylinder, a rod extending from each side of said second piston, valves on the free ends of said rod, said valves being adapted to open and close passages in said pipes, a valve for controlling the movement of said second piston, a member adapted to actuate the last mentioned valve, a second cylinder having communication with the first cylinder, a piston in said second cylinder, a rod extending from the opposite faces of the last mentioned piston, and means on the ends of the last mentioned rod for actuating said member.

8. In a pumping system, the combination of: an hydraulic pump comprising a plunger carrying a piston; a pressure supply tank adapted to contain an operating liquid; pipes extending from said tank and to said pump; and an interposed operating head comprising means for varying the alternations of pressure through said pipes on opposite sides of said plunger, said means comprising a cylinder, a second piston adapted to reciprocate in said cylinder, a rod extending from each side of said second piston, valves on the free ends of said rod, said valves being adapted to open and close passages in said pipes, a valve for controlling the movement of said second piston, and means for controlling the last mentioned valve and for controlling the outlet of operating fluid from said pipes.

In testimony whereof, I have hereunto set my hand at Los Angeles, California, this 24th day of June, 1924.

CHARLES E. H. LLOYD.
